INTERNAL-COMBUSTION ENGINE

Application filed July 24, 1928, Serial No. 295,060, and in Mexico November 10, 1927.

The invention relates to improvements in internal combustion engines of a two stroke cycle, and more especially to airplane motors of this type. The improvements substantially consist in providing in the lower part of each cylinder a closed chamber, separated and independent from the crank case, in which chamber takes place the admission and preliminary compression of the crude gas, thereby impeding the passage of the gas through the crank case. By means of this compression chamber, special compressors and additional pistons are completely eliminated. The aforesaid admission and compression chamber is connected by an outwardly located conduit with the combustion chamber of the cylinder, both chambers being internally separated from each other by the piston.

20 Referring to the drawings,

Fig. 1 is a sectional view, in side elevation, of a cylinder and crank case embodying features of the invention.

25 Fig. 2 is a view of the same cylinder partly in section and partly in front elevation.

Fig. 3 is a sectional view of the bottom plate of the cylinder.

Referring to these drawings in detail, in which similar reference characters correspond to similar parts throughout the several views, the numeral 1 indicates a steel cylinder, the lower extremity of which is closed by a cup-shaped circular plate 2, having in its center a tubular guiding member 3 which extends inwardly into the cylinder 1 and serves as a guide for the rod 4 rigidly attached to the head of the hollow piston 5. The other end of said piston rod 4, which is preferably hollow in order to reduce its weight, is provided with a fork and connected by a cross pin to a short connecting rod 6, which in turn is connected to the crank shaft 7, the length of said piston rod 4 being calculated so that at the highest position of the piston 5 its joint with the connecting rod 6 enters from below into the tubular guide 3.

50 The upper extremity of cylinder 1 is closed by a circular plate or cover 8 of inwardly concave shape and having at its center a

threaded hole for receiving the spark plug 9. The head plate 8 is further provided with a number of radially extending vertical cooling fins 10 and with a plurality of seats 11 through which pass steel rods 12, the lower ends of which are screwed into the sides of the bottom plate 2, the head plate being pressed upon the cylinder 1 by nuts 13 screwed on the threaded upper ends of said rods 12. Both upper and lower edges of the cylinder 1 are recessed and enter into corresponding recesses in plates 2 and 8, in order to obtain a tight joint and make the whole cylinder practically of one piece. The cylinder 1 is surrounded by a plurality of cooling rings 14, the rods 12 passing through holes in said rings.

At a height determined by the length of the piston 5, the cylinder 1 is provided with two opposite openings 15 and 16, the first 70 of which (15) serves as in inlet for the gas into the combustion chamber of the cylinder, while the second opening 16 lets escape the burnt gases through the pipe 17. A further horizontal opening 18 is provided in the side 75 of the bottom plate 2, below the inferior edge of the cylinder 1 and on a vertical line with the opening 15, and both openings 15 and 18 are connected by an externally located conduit 19 of substantially triangular 80 shape with a broad base and narrow apex, said conduit having a third outlet communicating with a pipe 20 through which enters the gas from the carburetor. An automatic non-return valve 21 located within this pipe 85 20 permits the passage of the gas during the suction stroke and closes as soon as compression of the gas by the descending piston sets in. An oil feeding pipe 22 for lubricating the piston enters the upper and outer part of 90 the conduit 19.

The cylinder 1 is fastened with its bottom plate 2 by means of screws 23 to the crank case 24, the crank shaft 25 passing through the cover 26 of said crank case. The lubricating oil is contained within the crank case 24 and is splashed by the revolving crank on the piston rod 4, the long tubular guiding member 3 of said rod impeding the entrance 100

of more oil than is necessary for the thorough lubrication of the rod and piston.

As the piston is forced down by the explosion of the gas in the combustion chamber, the gas previously sucked in through the inlet 18 is compressed both in the chamber formed between the piston and the bottom plate 2, and in the conduit 19 connected with said chamber the capacity of which, as will be noted from Figure 1 of the drawing, is substantially equal to the capacity of the firing chamber and also of the compression chamber, so that a double amount of fuel is present in the compression chamber of the cylinder and the conduit than would be the case if a simple bye-pass or conduit of a small and uniform diameter were used. The compression increases in the conduit 19 until the inlet opening 15 has been freed by the descending piston, when the compressed gas is violently injected above the piston into the combustion chamber of the cylinder, its velocity of flow being increased by the tapered shape of the conduit 19 and its small opening 15, so that the said conduit acts on the principle of the vena contractu. On entering into the combustion chamber, its flow is deflected upwardly by the recessed projection 27 on the piston head, which causes it to rise to the top of the combustion chamber and to thoroughly expel the burnt gases through the escape pipe 17. The two opposite openings 15 and 16 are closed again almost instantaneously as the piston ascends on its return stroke into the combustion chamber, where the gas is again compressed and finally exploded.

Obviously, changes in the details of construction may be made without departing from the spirit of the invention, and we do not care to limit ourselves to any particular form or arrangement of parts.

What we claim is:

1. In an internal combustion engine, a cylinder having its extremity adjacent to the crank case closed by a bottom plate; a piston having a rod rigidly attached to its head, said rod passing through an opening in the bottom plate and having its other end connected by a pivoted member to the crank shaft; an externally located conduit connecting the compression chamber formed in the cylinder between said piston and said bottom plate, with the combustion chamber of said cylinder, said conduit being broadened at the lower side and progressively contracting to a small opening at its discharge point into the combustion chamber and being of a capacity substantially equal to that of the combustion chamber and of the compression chamber of the cylinder; means for impeding the return of the gas into the carburetor.

2. A combustion engine as claimed in claim 1, in which the piston has a recessed projec-

tion on its upper side to deflect the compressed gas upwardly in the combustion chamber when the piston is in the lower limit of its stroke and promote expulsion of burned gases through the exhaust.

In testimony whereof we affix our signatures:

CAMILO PEYNETTI VALDATA.
MANUEL CRESPO GARCIA.
